UNITED STATES PATENT OFFICE.

LEO PRANGE, OF BROOKLYN, NEW YORK.

DESIGN FOR A BUTTON.

SPECIFICATION forming part of **Design No. 21,318**, dated January 26, 1892.

Application filed December 18, 1891. Serial No. 415,552. Term of patent 3½ years.

To all whom it may concern:

Be it known that I, LEO PRANGE, of Brooklyn, Kings county, and State of New York, have originated and produced a new Design 5 for Buttons, of which the following is a specification.

I will describe a button embodying my design.

In the accompanying drawings, Figure 1 is 10 a front view of a circular button embodying my design. Fig. 2 is a perspective side view thereof.

My design comprises a group of small jewel-like figures A, (shown as arranged in arcs of 15 a circle,) a number of leaf-like or petal-like figures B, radiating therefrom and made in the form of jewels or provided with a number of facets, two straight rows of jewel-like figures C, extending across the button above the 20 leaf-like or petal-like figures B, and a num-

ber of arc-shaped lines D, representing rope or cord, arranged above the rows of figures C. I have shown arc-shaped border-lines E extending between the rows of figures C and the leaf-like or petal-like figures B. 25 The surface between the leaf-like or petal-like figures B, the rows of figures C, and the arc-shaped border-lines E is ornamented with fine lines, which may be broken or interrupted.

What I claim, and desire to secure by Letters Patent, is—

The design for a button, as herein shown and described.

In testimony whereof I have signed my name to this specification in the presence of 35 two subscribing witnesses.

LEO PRANGE.
